US0D1029938S

(12) **United States Design Patent** (10) **Patent No.:** **US D1,029,938 S**
(45) **Date of Patent:** **** Jun. 4, 2024**

(54) **CASE FOR REFILL LEAD**

(71) Applicant: **MITSUBISHI PENCIL COMPANY, LIMITED**, Tokyo (JP)

(72) Inventor: **Tsuyoshi Nishida**, Tokyo (JP)

(73) Assignee: **MITSUBISHI PENCIL COMPANY, LIMITED**, Tokyo (JP)

(**) Term: **15 Years**

(21) Appl. No.: **29/816,579**

(22) Filed: **Nov. 23, 2021**

(30) **Foreign Application Priority Data**

May 28, 2021 (JP) ..... 2021-011407 D

(51) **LOC (14) Cl.** **19-06**

(52) **U.S. Cl.**

USPC **D19/190**

(58) **Field of Classification Search**

USPC D14/411, 341, 480.3, 264; D19/117, D19/166, 917, 929, 933, 916, 902, 115, D19/142, 160, 163, 180, 186, 203, 133, D19/202, 201, 196, 195, 162; D18/14, D18/15, 16; D10/86, 34; D28/7, 77, 88, D28/89

CPC B43K 7/005; B43K 5/005; B25H 7/04

(57) **CLAIM**

The ornamental design for a case for refill lead, as shown and described.

DESCRIPTION

FIG. 1 is a perspective view 1 of a case for refill lead showing my new design;

FIG. 2 is a perspective view 2 thereof;

FIG. 3 is a front elevational view thereof; the rear elevational view is the same as the front elevational view;

FIG. 4 is a right side elevational view thereof; the left side elevational view is the same as the right side elevational view;

FIG. 5 is an enlarged top plan view thereof;

FIG. 6 is an enlarged bottom plan view thereof; and,

FIG. 7 is an exploded perspective view thereof.

The broken lines depict portions of the case for refill lead that form no part of the claim.

1 Claim, 4 Drawing Sheets
